(57) **CLAIM**

The ornamental design for a plug for a beverage container lid as shown and described.

DESCRIPTION

FIG. 1 is an isometric view of a plug for a beverage container lid showing my new design in an environment of use including a lid and a beverage container.

FIG. 2 is an isometric view thereof, with the exemplary lid and beverage container removed to show aspects of the design not visible when combined;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged isometric view thereof, taken from within portion "9" on FIG. 2;

FIG. 10 is an enlarged front elevation view thereof, taken from within portion "10" on FIG. 3;

FIG. 11 is an enlarged rear elevation view thereof, taken from within portion "11" on FIG. 4;

FIG. 12 is an enlarged left elevation view thereof, taken from within portion "12" on FIG. 5; and

FIG. 13 is an enlarged right elevation view thereof, taken from within portion "13" on FIG. 6.

The broken lines are shown for the purpose of illustrating parts of the article, environmental subject matter of an exemplary lid and beverage container, as well as the designation of enlargement views. None of the broken lines form part of the claimed design.

The plug is shown with symbolic breaks in the structure using broken lines. The appearance of any portions of the plug between the broken lines forms no part of the claimed design.
